US0D1091651S

(12) **United States Design Patent** (10) Patent No.: **US D1,091,651 S**
(45) Date of Patent: ** Sep. 2, 2025

(54) **COOLER**

(71) Applicant: **The Coca-Cola Company**, Atlanta, GA (US)

(72) Inventors: **Damian James Reece Mycroft**, Decatur, GA (US); **Alison Benz**, Atlanta, GA (US)

(73) Assignee: **The Coca-Cola Company**, Atlanta, GA (US)

(**) Term: **15 Years**

(21) Appl. No.: **29/931,941**

(22) Filed: **Mar. 11, 2024**

(51) LOC (15) Cl. **15-07**

(52) U.S. Cl.

USPC **D15/79**

CLAIM

The ornamental design for a cooler as shown and described.

DESCRIPTION

FIG. 1 is a perspective view of a cooler, in accordance with our new design;

FIG. 2 is a front elevational view thereof;

FIG. 3 is a back elevational view thereof;

FIG. 4 is a right side view thereof;

FIG. 5 is a left side view thereof;

FIG. 6 is a top view thereof; and,

FIG. 7 is a bottom view thereof.

(Continued)

The dash-dash broken lines shown illustrate portions of the cooler that form no part of the claimed design.

1 Claim, 6 Drawing Sheets
